UNITED STATES PATENT OFFICE.

MICHAEL COSTELLO, OF JERSEY CITY, NEW JERSEY.

FIRE-ALARM APPARATUS.

Application filed November 21, 1923. Serial No. 676,091.

To all whom it may concern:

Be it known that I, MICHAEL COSTELLO, a citizen of the United States, residing at Jersey City, in the county of Hudson and State 5 of New Jersey, have invented certain new and useful Improvements in a Fire-Alarm Apparatus, of which the following is a specification.

This invention relates to improvements in 10 fire alarm apparatus.

The primary object of this invention is the provision of a novel type of fire alarm apparatus which is automatic in operation, embodying a circuit maker and breaker arrangement which will operate automatically upon the approach of fire to sound an appropriate fire alarm signal; or automatically control any of several mechanisms, such as close a gas valve in the burning 20 building; shut off electric current in the burning building; or close bulkhead doors or the like in factories, mines, or buildings.

A further object of this invention is the provision of a fire alarm system which may be used in buildings, especially buildings of 25 many stories, for indicating upon which floor a fire has broken out.

A further object of this invention is the provision of a novel safety switch for fire 30 alarm systems embodying a highly inflammable flash member normally adapted to maintain the switch open, but which upon the approach of fire will be instantly destroyed to permit the closing of the switch 35 for alarm actuation.

A further object of this invention is the provision of a novel contact arrangement for a fire alarm switch of the above mentioned character.

Other objects and advantages of this invention will be apparent during the course 40 of the following detailed description.

In the accompanying drawings, forming a part of this specification, and wherein 45 similar reference characters designate corresponding parts throughout the several views.

Figure 1 is a side elevation of the improved fire alarm safety switch, showing 50 novel features thereof and the connection of circuit wires thereto.

Fig. 2 is a bottom plan view of the improved switch illustrated in Figure 1.

Fig. 3 is a cross sectional view taken

through the improved safety switch, showing the same in closed relation for the actuation of a fire alarm circuit or the like.

Fig. 4 is a cross sectional view taken through the improved safety switch, showing the details substantially illustrated in Figure 3, although with the contacts of the switch in non-engaging relation.

Fig. 5 is an end elevation of a novel type of movable contact embodied in this invention.

Fig. 6 is a diagrammatic representation of a fire alarm system within which may be employed a plurality of circuits receiving the improved circuit maker and breaker devices.

Fig. 7 is a perspective view of the novel type of inflammable or flash member used in connection with this invention to maintain the switch in normally open relation.

In the drawings, wherein for the purpose of illustration is shown but the preferred embodiment of this invention, the letter A may generally designate the novel type of safety switch, which may be used in a wiring system B in a normally open relation, although when closed incident to automatic operation as will be subsequently described, adapted to actuate a fire alarm signal C, or operate any type of mechanism D.

Referring to the improved safety switch A, the same is a complete unit, ready for installation in a building, preferably upon the ceiling. It includes a substantially polygonal shaped base 10, which may be of any approved material, and which is provided with suitable openings 11 therein for the reception of securing elements, whereby the switch A may be secured by means of its base 10 to an iron beam, rafter or other support of the building in which the same is to be placed. Inwardly of the exposed surface 15 of the base 10, an opening 16 is provided, which is adapted to receive the screw threaded end 17 of a hollow cylindrical shaped guide sleeve 18, whereby the same 100 may be secured at an axis substantially at right angles to the plane defined by the base 10; the opening 19 provided by the guide sleeve 18 being open at the free end 20 of said guide sleeve.

A substantially Z-shaped bracket 22, which may be of metal, is also secured as by an attaching flange portion 23 to the ex-

posed surface 15 of the base 10, with the flange portion 23 lying flush on the surface 15 and secured in such position by means of screws 24. The body portion 25 of the bracket 22 depends at right angles to base 10 and in parallelism with the guide sleeve 18, and at its lower end has a supporting leg or flange 26 arranged substantially at right angles to the body portion 25, and in a plane parallel with the base 10; said leg 26 extending beneath the guide sleeve 18, and having an opening 28 therein which aligns with the passageway 19 of the guide sleeve 18.

15 A substantially L-shaped metal contact 30 is provided in connection with the safety switch A, which embodies a portion 31 adapted to lie in flush abutting relation with the body portion 25 of the bracket 22, and 20 to be secured thereto by means of screws 32 or the like. The contact member 30 also includes the contact flange 33, which extends at right angles to the attaching portion 31, and is disposed in spaced parallel 25 relation over the supporting flange 26 of the bracket 22, between said flange 26 and the base 10. At its free end the flange 33 is provided with an opening 35 having a beveled edge which diverges toward the opening 28 of the bracket 22, and is in axial alignment with the passageway 19 of the guide sleeve 18 and with the opening 28 of the bracket flange 26.

30 A movable contact 37 in the nature of a cylindrical shaped plunger is slidably mounted within the passageway 19 of the guide sleeve 18, having the outer end 38 thereof tapering to a point. The cylindrical shaped movable contact 37 at its inner end provides a socket 40 which receives therein a compression spring 41 which is normally compressed intermediate the plunger 37 and the base 10, substantially as is illustrated in Figure 3 of the drawings, for 35 the purpose of forcing the movable contact 37 toward the fixed contact 30, and to direct the tapered end or head portion 38 so that it engages the contact 30 in the beveled edged opening 35 thereof. A terminal attaching flange 47 is annularly formed about the exposed end of the movable contact 37, at the juncture of the tapered head portion 38 with the body of the movable contact 37; said flange having a series of openings 48 40 therein. An exterior spiral compression spring 50 is provided, in fixed relation about the exterior of the guide sleeve 18, at one end engaging the base 10, and at its other end engaging the flange 47 for the purpose 45 of urging the contact 37 toward the contact 30. In this connection it is to be noted that the spring 41 is enclosed entirely within the structure of the switch A, whereas the spring 50 is exposed and adds a reinforcing action to the spring 41 to perform

the function of normally urging the movable contact 37 into engagement with the fixed or stationary contact 30.

In connection with the stationary contact 30, a terminal clamping member 55 is employed, which includes an attaching portion 56 adapted to be clamped to the bracket 22 by one of the screws 32 which also secures the contact 30 thereto, so that the terminal clamp is in conducting relation with the contact 30. The terminal clamp 55 further embodies an outstanding attaching portion 57, which at its free end is inturned, as at 58, to provide a socket 59 wherein may be disposed the stripped portion of a conducting wire 60^a of the circuit within which the switch A is to be located. The movable contact 37 is adapted to receive a conducting wire 61^a, by means of connection to the openings 48 of the flange 47 of said movable contact 37.

From the above description of the safety switch A it is apparent that the same may be installed in any suitable location in a building with a minimum amount of labor and 90 passing of time. The parts of the improved switch are readily removable and the connecting wires may be attached thereto without the necessity of detachment of parts.

In order to maintain the contacts 30 and 37 in a normally spaced relation so that the switch A will normally maintain the circuit in which the same is disposed open, a novel type of flash member 60 is employed, which is formed of some highly 100 inflammable or combustible material, such as pyroxylin. It includes the body portion 61 having a locating projection 62 extending outwardly from a surface thereof. The body portion 61 is preferably polygonal shaped in formation, and on all 105 sides except one is provided with the laterally extending triangular shaped flash projections 65 which extend outwardly 110 from the body portion 61 in the same direction, and in planes at obtuse angles with respect to the plane of the body portion 61. With respect to the positioning of the flash member 60 upon the safety switch A, the same normally rests upon the supporting 115 flange 26 of the bracket 22, with the locating lug 62 resting in the opening 28 of the supporting flange 26. In this relation the side or edge of the body 61 which is free of any of the projections 65 faces the body portion 25 of the bracket 22, and the flash projections 65 extends laterally of and 120 downwardly from the bracket flange 26. In this position of the flash member 60 the pointed or tapered head 38 of the movable contact 37 engages the body 61 of the flash member 60, which now covers the aperture 28, and thus maintains the movable contact 37 out of engagement with the contact 30, notwithstanding the action of its springs 125 130

41 and 50; the tapered surface of the head 38 thus being disposed in spaced relation with the beveled edges of the aperture 35 of the contact 30, substantially as is illustrated in Figure 4 of the drawings, and normally maintaining the circuits which are controlled by the switch A open. It is to be particularly noted that the flash member 60 is so positioned that the same is exposed in the room of a building at all times, and the projections may be readily reached, either for manual removal, or by flames should the building be on fire. By having the projections extending downwardly as shown in Figures 1 and 4 their lower ends may be readily ignited and the flame will travel upwardly and quickly destroy the flash member so that the springs actuating the movable contact will move the same into engagement with the stationary contact for closing the circuits of the fire alarm.

Referring to the wiring system B which may be placed in any building having a plurality of floors, an annunciator board 75 may be provided, having suitable annunciators 76 thereon for each floor of the building, and suitable individual circuits 78 for each floor of the building and within which the respective annunciators 76 are positioned. Each circuit 78, of course, has one of the safety switches A located therein. The circuits 78 may receive their supply of electrical energy from a common source 80, and have a common warning signal 81 located therein adapted for actuation upon closing of any of said circuits. In connection with the wiring system B, where it is desirable to operate some mechanism such as a valve, relay, or some heavy mechanism such as a bulkhead door, a local circuit 85 may be operated by one or more of the safety switches A, substantially as is diagrammatically illustrated in Figure 6, for the actuation of a relay 86 in said local circuit; said relay 86 being the means of closing a switch mechanism 87 in a high powered circuit 88, and in which high powered circuit 88 suitable means may be placed for actuating any of the above mentioned mechanisms.

From the foregoing description of this invention it is apparent that a novel type of fire alarm apparatus has been provided which is relatively simple in operation, yet positive in action to perform the purposes for which it is adapted. The functions which the improved fire alarm apparatus serve are not limited to the sounding of a warning signal, but the improved circuit maker and breaker switch A may be embodied in circuits adapted for the actuation of any suitable mechanism desired. The fact that the inflammable flash member 60 is placed in an out of the way position, and not between the movable and fixed contacts

insures that whenever the point or tapered head 38 of the movable contact 37 penetrates the body 61 of the flash member 60, that the contacts of the switch A will meet and close the circuit, and the merely partial destruction of the flash member 60 cannot interfere with such circuit closing. The flash member 60 is at all times accessible for test purposes and may be readily reached by flames, embers, and the like which threaten to destroy the building in which the improved switch A is positioned.

Various changes in the shape, size, and arrangement of parts may be made to the form of the improved fire alarm apparatus herein shown and described, without departing from the spirit of the invention or the scope of the claims.

I claim:

1. A safety switch of the class described comprising a support, a bracket carried by the support and having an arm extending substantially parallel to said support, a fixed contact carried by the bracket having a portion extending between said support and the arm of said bracket and provided with an opening, a movable contact normally urged toward the aperture in said fixed contact to extend therethrough, and an inflammable member supported by the arm of said bracket for engaging said movable contact to maintain the contacts out of relative engagement, but upon destruction permitting movement of the movable contact into engagement with the fixed contact.

2. A safety switch comprising a support, a bracket carried by the support, a fixed contact supported by the bracket having an opening therein, a movable contact, means normally urging the movable contact into the opening of said fixed contact, and a destructible member adapted to be supported by said bracket on the opposite side of said fixed contact with respect to said movable contact adapted to engage the latter whereby to support it out of engagement with the fixed contact, said movable contact upon destruction of said destructible members adapted to engage the fixed contact for closing a circuit.

3. A safety switch comprising an attaching base, a tubular guide member supported in substantially right angled relation by said base defining an open passageway therein, a slideable member in the passageway of said tubular member, having a socket recess in the inner end thereof, a compression spring supported in said socket recess within the slideable member and in the guide sleeve for normally urging the slide member outwardly of said guide sleeve passageway, an annular flange supported at the outer portion of said slide member, a compression spring between said flange and the base for normally urging the slide member

outwardly from said guide sleeve, a bracket supported by the base providing a portion which extends across the outer end of said slidable member and has an opening therein for receiving the slidable member at its free end, and a contact carried by said bracket providing an apertured portion which extends across the space between the slidable member and the apertured portion of said bracket for receiving the outer end of the slidable member in the aperture thereof.

4. A safety switch comprising an attaching base, a tubular guide member supported in substantially right angled relation by said base defining an open passageway therein, a slidable member in the passageway of said tubular member, having a socket recess in the inner end thereof, a compression spring supported in said socket recess within the slidable member and in the guide sleeve for normally urging the slidable member outwardly of said guide sleeve passageway, an annular flange supported at the outer portion of said slide member, a compression spring between said flange and the base for normally urging the slide member outwardly from said guide sleeve, a bracket supported by the base providing a portion which extends across the outer end of said slidable member and has an opening therein for receiving the slidable member at its free end, a contact carried by said bracket providing an apertured portion which extends across the space between the slidable member and the apertured portion of said bracket for receiving the outer end of the slidable member in the aperture thereof, and a flash member of inflammable material adapted to be supported by the apertured portion of said bracket whereby to hold the slidable member in supported disengaged relation with the fixed contact.

5. A safety switch comprising a base, a

slidable member providing a pointed head, 45 means for guiding and normally urging the slidable member outwardly from said base, a support carried by the base and having an arm extending parallel to the base, a fixed contact carried by the support and 50 having a portion extending between the arm and base parallel to the base and provided with an opening adapted to receive the pointed head of said slidable contact and of less diameter than the diameter of 55 the largest portion of the pointed head, and a flash member adapted to be supported by the arm of said support to maintain the pointed head out of normal engagement with said fixed contact.

6. As an article of manufacture, a flash member for safety switches formed of highly inflammable material and including a body portion and flash projections extending therefrom.

7. As an article of manufacture, an inflammable flash member for safety switches comprising a body portion of plane formation, and outwardly extending pointed flash projections extending therefrom.

8. As an article of manufacture, an inflammable flash member for safety switch comprising a body portion of plane formation, and outwardly extending pointed flash projections extending downwardly therefrom at an angle of less than 180° with respect to said body portion.

9. As an article of manufacture, an inflammable flash member for safety switches comprising a body portion of plane formation, outwardly extending pointed flash projections extending downwardly therefrom at an angle of less than 180° with respect to said body portion, and a centering lug carried outwardly of a side surface of 85 said body portion.

MICHAEL COSTELLO.
